UNITED STATES PATENT OFFICE.

GEORGE ALVAH N. COPPEDGE, OF WINSTON-SALEM, NORTH CAROLINA.

GARMENT.

1,235,441.

Specification of Letters Patent.

Patented July 31, 1917.

Application filed October 13, 1916. Serial No. 125,423.

To all whom it may concern:

Be it known that I, GEORGE ALVAH N. COPPEDGE, a citizen of the United States, residing at Winston-Salem, in the county of Forsyth and State of North Carolina, have invented a new and useful Garment, of which the following is a specification.

This invention has reference to garments, and particularly to upper garments, and is 10 designed to provide a shirt or shirt-waist or like garment with suspending means for nether garments, whereby the weight of the nether garment is carried by the shoulders of the wearer.

15 For convenience of description the invention will be considered as applied to a man's shirt, although applicable to shirt-waists and the like, and the suspending means will be referred to as suspenders without necessarily limiting such means to the articles 20 ordinarily known as suspenders.

In accordance with the present invention the suspenders are made a permanent part of the shirt and no part of the suspenders is 25 loosely dangling when not fastened to the garment to be sustained.

The shirt is provided on each side with a band of some strong material, such as tape, in encircling relation to a corresponding 30 arm-hole of the shirt, and so spaced therefrom as to pass over the shoulder of the wearer. The ends of the band are brought together at a suitable distance below the arm-hole and there sewed to the body of 35 the shirt for a suitable distance toward the bottom of the shirt. From a point about midway of the arm-hole to a point near where the top of the nether garment reaches, which last-named point may be considered

40 as about coincident with the waist line, the suspending band is free from attachment to the shirt, and is somewhat shorter than the normal length of the shirt between the points named. In this way there is produced 45 a fullness in the shirt so that when a weight is applied to the band at the waist line, such weight is borne entirely by the shoulders of the wearer and the body of the shirt is wholly relieved from the weight. The band

50 where made fast to the shirt adjacent to the waist line is secured flat thereagainst and is provided with a series of buttonholes extending not only through the band, but through the material of the shirt. The band is applied to the inner face of the shirt, while the

buttonholes are accessible through the outer face of the shirt.

It is the common practice with trousers to have buttons on the inner face of the waist band of the trousers, and buttons 60 which are usually located at about diametrically opposite points of the waist band of the trousers may be readily engaged in appropriate ones of the buttonholes. In this way the trousers are sustained in a manner 65 similar to the use of ordinary suspenders, but the suspenders are hidden from sight, being on the inner face of the shirt and the weight is borne entirely by the shoulders of the wearer, while the fullness of the shirt 70 prevents any drawing or puckering.

The invention will be best understood from a consideration of the following detailed description, taken in connection with the accompanying drawings, forming part 75 of this specification, with the further understanding that while the drawings show a practical form of the invention, the latter is not confined to any strict conformity with the showing of the drawings, but may be 80 changed and modified so long as such changes and modifications come within the scope of the appended claims.

In the drawings:—

Figure 1 is a view of the inside of a shirt 85 with the invention applied, the shirt being spread open.

Fig. 2 is a section on the line 2—2 of Fig. 1, but drawn on a larger scale and showing a small portion of a nether garment attached to the shirt.

Fig. 3 is a section on the line 3—3 of Fig. 1 and also showing a small portion of a nether garment.

Fig. 4 is a view showing a strip of tape 95 in position to be sewed into place in the shirt.

Referring to the drawings there is shown a shirt 1 which may be taken as indicative of any type of shirt or shirt-waist and without any attempt to indicate exactitude of proportions. The shirt is provided with sleeves 2 and has armholes 3 where the sleeves join the body of the shirt.

On each side of the shirt there is applied 105 a band 4 which may be made of tape of suitable width and length and sufficiently strong for the purpose. The tape for a portion of its length somewhat to one side of the mid point of the tape is formed into a loop 5 110

sewed to the shoulder portion of the shirt in encircling spaced relation to the respective armhole 3, the spacing being such that when the shirt is applied to a wearer, the portion 5 of the band or tape 4 will engage over and about the shoulder of the wearer and extend over the chest and down the back for a short distance, the sewing involving about half the height of the armhole. This leaves 10 two strips 6, 7 of the tape which are carried downwardly toward the waist line of the shirt and are brought together at or a little above the waist line where the two legs 6 and 7 of the loop 5 are sewed together and to 15 the body of the shirt, the point of sewing being such that the two tape strips or bands are located about oppositely one with respect to the other. One leg of the loop, say, the leg 7, is shorter than the leg 6, so that the 20 two legs where sewed together overlap for but a relatively short distance, the tape of the leg 6 having a continuation 8 which is also sewed to the fabric of the shirt and may be continued along the underarm seam of 25 the shirt to the bottom of said seam.

Formed in the overlapping portions of the legs 6 and 7 and through the corresponding portion of the shirt is a button hole 9, while below the buttonhole 9 are other buttonholes 10 formed through the continuation 30 8 and the fabric of the shirt. In this manner the buttonholes, which are arranged in upright series, are accessible from the exterior of the shirt and a button 11 in a nether garment 12 may be readily secured in any 35 one of the buttonholes.

In order to indicate in the drawing where the suspending means is made permanently fast to the shirt, dotted lines 13 are used to 40 represent the lines of stitching. The leg portions 6 and 7 between the loop 4 and where the leg portions are connected together and to the body of the shirt, are loose, but the length of these loose portions is less than the 45 length of the corresponding portion of the shirt, which portion is indicated at 14.

When the shirt is put on and the nether garment 12 is also on the wearer the loop 5 of each band 4 engages over the shoulder of 50 the wearer. Then the buttons 11, of which there is assumed to be one on each side of the garment 12, are engaged in the buttonholes 9 or 10 as may be needed, and the weight of the nether garment is then sustained entirely by the loops 5 passing over the shoulders of the wearer and is transmitted 55 through the loose portions of the legs 6 and 7 where unattached to the shirt.

The series of buttonholes 9 and 10 provide for such adjustment as may be needed 60 to accommodate the shirt to people of different heights. In any event the button holes 9 and 10 are arranged at about the waist line, or sufficiently near thereto so as to sustain the nether garment in the customary position, and by providing an upright series of buttonholes the needed adjustment customarily provided for by buckles and the like is present in the garment described. Since the suspending devices represented by the tapes 4 carry all the weight of the nether garment the fullness 65 in the upper garment avoids any drawing or puckering thereof due to the weight of the nether garment. Because of this fullness 70 and because the suspending means are on the inside of the shirt out of sight, the presence of such suspending means is not noticeable and it is quite feasible to wear the shirt without any outside covering and without 75 necessitating the use of a belt to hold the nether garment in place.

The suspending tapes or bands are flexible and substantially inextensible and constitute permanent parts of the shirt with no 80 dangling or loose ends and no parts to be removed. This permits the shirt to be laundered in the same manner as though the suspending means were absent.

What is claimed is:—

An upper garment having on opposite sides sustaining means for a nether garment, each sustaining means comprising an inextensible band or tape in the form of a loop secured to the shoulder portion of the 90 upper garment within the latter in surrounding spaced relation to a corresponding armhole, with the sides of the loop separate from the upper garment and brought together at substantially the waist line of the 100 upper garment and there united one to the other and to the upper garment, and provided with a series of buttonholes extending in the direction of the longitudinal axis of the loop with each button hole opening 105 through both the tape and the material of the garment to receive a button fast to the nether garment.

In testimony, that I claim the foregoing as my own, I have hereto affixed my signature in the presence of two witnesses.

GEORGE ALVAH N. COPPEDGE.
